UNITED STATES PATENT OFFICE.

GEORGE BLOHM, OF EL CENTRO, CALIFORNIA.

COTTON-CULTIVATOR.

1,257,792.

Specification of Letters Patent. Patented Feb. 26, 1918.

Application filed May 11, 1917. Serial No. 167,982.

To all whom it may concern:

Be it known that I, GEORGE BLOHM, a citizen of the United States, residing at El Centro, in the county of Imperial and State of California, have invented new and useful Improvements in Cotton-Cultivators, of which the following is a specification.

This invention relates to cotton choppers, and cultivators and it has for its object to produce a machine of this class which will be of simple and improved construction.

A further object of the invention is to produce simple and improved means whereby adjustment of the chopping mechanism may be effected. A further object of the invention is to simplify and improve the construction of the chopping mechanism.

A further object of the invention is to produce simple and improved means for throwing the chopping mechanism in and out of gear.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention, it being, however, understood that no limitation is necessarily made to the precise structural details therein exhibited, but that changes, alterations and modifications within the scope of the claims may be resorted to when desired.

In the drawings:

Figure 1 is a top plan view of a machine constructed in accordance with the invention.

Fig. 2 is a side elevation of the same.

Fig. 3 is a bottom plan view.

Fig. 4 is a longitudinal sectional view taken on the line 4—4 of Fig. 1.

Fig. 5 is a transverse sectional view taken on the line 5—5 in Fig. 1.

Fig. 6 is a front view.

Fig. 7 is a perspective detail view of the chopping device detached and with parts broken away.

Corresponding parts in the several figures

of the drawings are denoted by like characters of reference.

The main frame of the improved machine is composed of side members 15 which are connected together and spaced apart by cross bars 16. The side bars 15 are provided with bearings 17 for the axle 18 carrying the ground wheels 19. The ground wheels may be fixed on the axle or they may be connected therewith by clutch devices of well known construction which, however, it is not considered necessary to illustrate, such clutch devices being well known in the art and not herein claimed. The side members 15 have been shown as being constructed of channel beams having outer and inner flanges 20, 21 on which standards 22 carrying cultivator blades or shovels 23 are adjustably secured by clips or clamps 24. A longitudinal frame bar 25 is securely mounted on some of the cross bars 16 including the foremost one, said longitudinal frame bar being provided at its forward end with a downturned lug or flange 26 on which a guide member 27 is bolted or otherwise secured, said guide member being provided with grooved flanges wherein is guided the vertical limb 28 of an L-shaped bracket B the other limb of which 29 extends rearwardly in an approximately horizontal plane, said limb carrying the driver's seat 30 which is additionally supported by a threaded post or bolt 31 that extends downwardly through the frame bar 21 and is provided with adjusting nuts 32. A second threaded post or bolt 33 rising from the frame bar 25 and extending also through the foremost cross bar 16 extends through the horizontal limb 29 of the bracket B and is provided with adjusting nuts 34.

Connected with one of the intermediate frame bars 16 is a downwardly extending bracket 35 having a bearing through which extends one end of a longitudinal shaft 36 the other end of which has a bearing in the vertical limb 28 of the bracket B. Vertical adjustment of said bracket may be effected by means of the adjusting nuts 32 and 34 on the posts 31 and 33, respectively, thereby permitting the forward end of the shaft to be raised or lowered. The adjustment, how-

ever, is not so extensive as to render a corresponding adjustability of the bracket 35 necessary since the shaft may be permitted to rock in its bearing on said bracket 35 5 sufficiently to permit the necessary degree of adjustment of the forward end of the shaft. The shaft 36 carries a pinion 37 which meshes with a crown gear 38 on the axle 18, the shaft being pressed in a rearward direction by a spring 39 coiled on said shaft between the pinion 37 and the vertical limb 28 of the bracket B, the parts being so arranged and proportioned that by the action of said spring the pinion 37 will be 10 held in mesh with the crown gear 38. The hand lever 40 is provided having a fork 41, the limbs of which are apertured for the shaft 36, the latter being provided with a collar 42 fixed between the limbs of the fork 15 so that by means of the lever the shaft may be forced forwardly against the tension of the spring 39 until the pinion 37 is out of mesh with the crown gear 38, thus interrupting the rotation of the shaft.

20 The shaft 36 carries at its forward end a chopping device, the same consisting of a flanged hub 43 which is securely mounted on the shaft and with the forward face of which a clamping disk 44 is connected by means of bolts 45, said hub and disk clamping between them the angular bracket 46 with which other angular brackets 47 are connected by bolts 48. The brackets 47 have wings that extend radially with respect to the axis of 25 the shaft 36, said wings carrying hoes or cutting blades 49 that are secured thereon by means of bolts 50. The bolts 48 which connect together the angular brackets 46 and 47 constitute pivot members whereby the 30 hoes or cutting blades may be disposed at various angles with respect to the axis of the shaft 36. When the machine is used for chopping out cotton, only one or two hoe blades need be employed. The cutting 35 mechanism may, however, be utilized for tilling and pulverizing the soil and when the machine is used for this purpose, a greater number of cutting blades may be used, there being no intention of limiting myself to any 40 particular number.

50 The main frame is provided with arms or brackets 51 that extend forwardly from the side members and which are connected together by means of an arch member 52 the 55 limbs of which are also connected with the side members of the main frame by means of brace bars 53 the forward ends of which may be utilized for the attachment of draft although the arch is provided with a centrally disposed draft member or clevis 54 with 60 which a tongue may be connected. The machine may be drawn by one or more draft animals, according to the size thereof, and when several rows of plants are to be simultaneously operated upon, or when the soil is

to be tilled, a plurality of machines may be suitably attached to and drawn by a single tractor.

From the foregoing description, taken in connection with the drawings hereto annexed, the operation and advantages of this invention will be readily understood. Ordinarily the machine will be drawn by two draft animals attached thereto in the most convenient way, the machine straddling the 70 row of plants while the draft animals walk between the rows. As the machine advances, the shaft 36 will be rotated, and the row of young plants will be chopped out at predetermined intervals, the cultivator 75 blades or shovels carried by the standards serving to throw the soil toward or from the growing plants, as may be required, according to the arrangement of the said blades or shovels. By raising or lowering the L-shaped 80 bracket B, the cutting apparatus may be correspondingly raised or lowered so as to engage the ground to the required depth. By manipulating the hand lever 40, the cutting mechanism may be thrown out of gear 85 when desired.

Having thus described the invention, what is claimed as new is:

1. In a machine of the class described, a wheel supported frame having a revolving 95 axle, a bar extending longitudinally of the frame and having a lug at its front end, a guide fixed on said lug, an L-shaped bracket having a vertical limb engaging the guide and a rearwardly extending horizontal limb, 100 means for effecting vertical adjustment of the L-shaped bracket with respect to the longitudinal frame bar, a longitudinal cutter carrying shaft having its forward end journaled in the vertical limb of the L-shaped bracket, and an additional bearing for the 105 rearward end of the cutter carrying shaft.

2. In a machine of the class described, a wheel supported frame having a revolving axle, a bar extending longitudinally of the 110 frame and having a lug at its front end, a guide fixed on said lug, an L-shaped bracket having a vertical limb engaging the guide and a rearwardly extending horizontal limb, means for effecting vertical adjustment of 115 the L-shaped bracket with respect to the longitudinal frame bar, a longitudinal cutter carrying shaft having its forward end journaled in the vertical limb of the L-shaped bracket, an additional bearing for 120 the rearward end of the cutter carrying shaft, means for transmitting motion from the axle to the cutter carrying shaft, and means for throwing said transmission means out of gear.

3. In a machine of the class described, a wheel supported frame having a longitudinal frame bar provided with a lug at its front end, a guide fixed on said lug, an L-shaped bracket having a vertical limb en- 125

gaged in said guide and a rearwardly extending horizontal limb, a seat carried by the horizontal limb, threaded members connecting the horizontal limb of the L-shaped bracket with the longitudinal frame bar, adjusting nuts on said threaded members, a cutter carrying shaft deriving motion from

the supporting wheels and having its forward end journaled in the vertical limb of the L-shaped bracket, and an additional bearing for the rearward end of the cutter carrying shaft. 10

In testimony whereof I affix my signature.
GEORGE BLOHM.
